Primary Examiner—James R. Largen

[57] CLAIM

The ornamental design for an aerator motor assembly for a sewer system, substantially as shown and described.

DESCRIPTION

FIG. 1 is a front elevational view of an aerator motor assembly for a sewer system embodying my new design, the rear being a mirror image of the front shown; FIG. 2 is a top plan view thereof; FIG. 3 is a bottom plan view thereof; FIG. 4 is a left end elevational view thereof; and FIG. 5 is a right end elevational view thereof.
